M. F. Funeral

Attorney.

UNITED STATES PATENT OFFICE.

IRA D. WALTER, OF HARRISBURG, ARKANSAS, ASSIGNOR OF ONE-FOURTH TO JOSIAH BRINKERHOFF AND ONE-FOURTH TO CHARLES R. FRENCH, BOTH OF HARRISBURG, ARKANSAS.

METAL-FELLY WHEEL.

Application filed December 22, 1923. Serial No. 682,273.

To all whom it may concern:

Be it known that I, IRA D. WALTER, a citizen of the United States, residing at Harrisburg, in the county of Poinsett and State of 5 Arkansas, have invented a certain new and useful Improvement in Metal-Felly Wheels, of which the following is a full, clear, and exact description.

This case is a continuation in part of my 10 application for patent for metal felly wheels, filed September 27, 1922, Serial No. 590,924.

This invention relates to that class of wheels in which a metal felly or rim replaces the ordinary wooden felly.

15 In wheels of the usual construction having either metal or wooden fellies, a chief source of weakness lies in the tenons formed on the outer ends of the spokes to engage the felly. Of necessity the spokes must be cut down to 20 a small cross-section in the tenon in order to afford a sufficient shoulder on the end of the spokes to support the radial stresses of the wheel when under load. The results are that the action of the varying heat and cold and 25 wet and dry conditions and the expansion and contraction incident thereto, have a tendency to loosen the spokes in their engagement with the felly, which immediately sets up wear upon the tenons and ultimately 30 produces a shakily wheel. In this weakened condition the wheel is liable to collapse at any time under severe side-thrust, in which case, with wheels of metal felly construction, the portion which gives way is invariably 35 the tenons on the ends of the spokes. In wheels of wood felly construction the felly sometimes gives way by splitting lengthwise and spreading laterally through the holes which engage with the spoke tenons. To insure 40 against this possible splitting of the felly necessitates making it heavier in cross-section, which is not desirable, or reducing the size of the holes for receiving the spoke tenons, which is impractical on account of 45 the necessity of preserving the maximum of strength in these parts.

In the present invention a steel felly having the maximum of strength and wear resisting qualities is combined with wood 50 spokes in a wheel construction possessing all of the inbuilt compression and tension necessary to provide a substantial and resilient wheel, with the use of only simple and well-

known methods of assembling the parts which compose the completed wheel aside 55 from my improvements.

The invention consists of a metal felly or rim constructed and arranged to receive any desired style of tire, whether solid, cushioned or pneumatic, the spokes fitting flush 60 against the inside surface of the felly or rim, that is to say, being without tenons or otherwise reduced ends to enter the felly or rim, and these spokes and the felly being connected by fasteners driven into the ends of the 65 spokes from the outside of the felly, as I will proceed now to explain and finally claim.

In the accompanying drawings illustrating the invention, in the several figures of which like parts are similarly designated, Figure 1 70 is an elevation of a conventional form of a portion of a wooden spoke automobile wheel, having the metal felly and the felly and spoke connection of this invention, the latter being shown in partial section. Fig. 2 is a 75 top plan view of a portion of the felly and one of the fasteners, on a larger scale. Fig. 3 is a sectional elevation, taken on line 3—3 of Fig. 2. Fig. 4 is a view similar to Fig. 2, but showing a modification including means 80 for positively connecting the spoke fastener with the felly. Fig. 5 is a sectional elevation, taken on line 5—5 of Fig. 4. Fig. 6 is a view similar to Fig. 5 but showing a different form of means for positively connecting 85 the spoke fastener with the felly. Fig. 7 is a view similar to Figs. 3, 5 and 6 but showing a modification. Fig. 8 shows, on a smaller scale, a further modification in which a rim is mounted directly on the spokes. 90

The hub 1 and spokes 2 may be of any approved construction and assembled in any approved way. The outer ends of the spokes are neither provided with tenons nor reduced to enter or engage the felly, but they 95 are cut off square so as to fit flush against the inner surface of the felly, (see spokes A and B of Fig. 1).

The felly 3 is of metal, shrunk upon or otherwise fitted to the spokes. This felly 100 may be of any cross sectional form to suit the tire appliances to be used, that shown in the drawings having lateral flanges 4 and 5 adapted to receive a demountable rim for a pneumatic tire.

105 The felly and the spokes are connected by

means of spoke fasteners 6, which are driven into the tenonless ends of the spokes through holes 7 in the felly. These fasteners may be of a variety of forms so long as they have a part which may be passed from the outside through a hole in the felly into engagement with the spoke and whether the spoke be previously prepared to receive it or not. In the preferred form each fastener comprises a tubular dowel having a cutting edge 8 adapted to be driven into the end of the spoke through a hole 7 in the felly in which it enters with a drive fit. Obviously the dowel will be driven into the spoke to such an extent that its outer end is substantially flush with the outer surface of the felly, thereby providing a projection from the spoke of a length substantially equal to the thickness of the material of the felly. This engagement between the ends of the dowels or spoke fasteners 6 and the felly has been found to provide an effective, rigid and permanent connection between the spokes and felly. Inasmuch as by driving the fasteners in so that their outer ends lie substantially flush with the outer surface of the felly a smooth outer surface is provided. This preferred form of the invention lends itself readily to a wheel construction in which a clincher rim 3', Fig. 8, may be mounted directly upon and attached to the spokes, for the reason that there will be no projections to contact with and cause wear of the inner tube of a pneumatic tire. When the dowels or fasteners are tubular, as in the preferred form of the invention, a slight depression is formed within each fastener between its outer end and the end of the spoke when the fasteners are driven in, which depression is equal in dimensions to the hole 7 minus the cross-sectional thickness of the fastener, and when used with a clincher or other rim attached directly to the spokes, this depression may be filled, as shown at 7' in Fig. 8, so as to provide a uniform surface, in any suitable manner. I propose to use for this purpose the discs produced by punching the holes 7 and re-punching these discs to a reduced diameter to provide a drive fit in the ends of the fasteners.

Although I have found that it is not essential, it may be found expedient to so form the spoke fasteners as to provide for their positive connection with the felly, and this connection may be made in a variety of ways, as shown, for example, in Figs. 4 to 7 inclusive.

In Figs. 4 and 5 I have shown the spoke fastener as having a part 9 adapted to be passed from the outside through a hole 7 in the felly into engagement with the spoke and having the cutting edge 8 and the extensions 10 overlying the felly on the outside, and secured to the felly in any suitable way, as by rivets 11, Figs. 4 and 5, or by having

their ends extended as at 12 and turned down through holes 13 in the felly and clinched or upset, as shown in Fig. 6.

As shown in Fig. 7, I may use a fastener having a solid projection 14 which is driven from the outside of the felly through a hole therein into a bore 15 in the tenonless end of the spoke. Also as shown in Fig. 7 the holes 16 in the felly may be countersunk or tapered and the ends of the fastener upset within these holes.

In the preferred construction, the fastener at its cutting edge 8 has a cylindrical exterior and a tapered interior, so that when it is driven into the end of the spoke there will be no tendency to split the spoke, but there will be a tendency to compress the material of the spoke within the tube and thereby solidify and consequently strengthen the spoke at its union with the felly.

By the construction described, a wooden spoke wheel may be readily and accurately assembled, and the felly or rim applied with equal facility and held in place with the utmost security. There is no tenoning of the felly end of the spokes, and in the preferred construction the full cross-sectional area of the spokes is retained and additional transverse strength is imparted thereto by reason of the compression of that portion of the spoke ends which is forced within the tapered interior of the tubular fasteners in forming the union of the spokes with the felly. The spokes are held in true radial position, without the possibility of displacement either circumferentially or transversely with relation to the felly, under normal conditions, and the liability of the spokes and felly wearing loose is greatly reduced, if not altogether eliminated.

Variations in details of construction are permissible within the principle of the invention and the claims following, and it is to be understood that the claims are intended to include and cover the use of the invention whether a felly or a rim be used in contact with the spokes.

What I claim is:—

1. In a spoked wheel, a metal felly or rim provided with perforations equal in number to the number of spokes, spokes having tenonless ends butted flush against the inner surface of the felly or rim, and tubular spoke fasteners having cutting edges and extending through the perforations in the felly or rim and driven into and embedded in the ends of the spokes.

2. In a wheel, wooden spokes, and a metal felly provided with perforations equal in number to the number of spokes, said wooden spokes having tenonless ends butted flush against the inner surface of the felly, and fasteners having portions passed through the felly from the outside thereof and into the tenonless ends of the spokes.

and also having extensions overlying the felly and clinched thereto.

3. In a wheel, wooden tenonless spokes and a metal felly fitted flush to the tenonless 5 ends of the spokes and having as many perforations as there are spokes, and fasteners having tubular portions extending through the perforations in the felly and provided with cutting edges driven into the tenonless 10 ends of the spokes.

4. In a spoked wheel, a metal felly provided with perforations equal in number to the number of spokes, spokes having tenonless 15 ends butted flush against the inner surface of the felly, and spoke fasteners having tubular portions provided with cutting edges, said tubular portions extending through the perforations in the felly and being driven 20 into and embedded in the ends of the spokes, and means to rigidly fix the fasteners on the 25 felly.

20 of the spokes, said spoke fasteners having extensions overlying the felly on the outside and secured to the felly.

5. In a spoked wheel, a metal felly provided with perforations equal in number to

the number of spokes, spokes having tenonless 25 ends butted flush against the inner surface of the felly, and spoke fasteners having tubular portions cylindrical on the outside and tapered on the inside to form cutting 30 edges and extending through the perforations in the felly and driven into and embedded in the ends of the spokes.

6. In a spoked wheel, a metal felly provided with perforations equal in number to the number of spokes, spokes having tenonless 35 ends butted flush against the inner surface of the felly, and spoke fasteners having tubular portions having cutting edges, said tubular portions extending through the perforations in the felly and being driven 40 into and embedded in the ends of the spokes, and means to rigidly fix the fasteners on the felly.

In testimony whereof I have hereunto set my hand this 18 day of December A. D. 45 1923.

IRA D. WALTER.
